UNITED STATES PATENT OFFICE.

GEORGE HAYES, OF NEW YORK, N. Y.

METALLIC-SKYLIGHT BAR.

SPECIFICATION forming part of Letters Patent No. 282,191, dated July 31, 1883.

Application filed November 14, 1882. (No model.)

To all whom it may concern:

Be it known that I, GEORGE HAYES, a resident of the city, county, and State of New York, have invented a new and useful skylight bar or rafter for metallic skylights, conservatory-roofs, &c., of which the following is a specification.

This invention has for its object lightness, cheapness, strength, and durability, combined with facility of glazing and reglazing; also to effectually provide against leakage from any cause. The nature thereof consists in the peculiar formation of the bar or rafter of which the skeleton of the skylight structure is composed. This bar or rafter I construct mainly of sheet metal—such as galvanized iron—in such manner that it forms a vertical central portion, having lateral flanges at its upper part forming ledges for the support of glass plates, and at its lower part gutters to collect and carry off the water of condensation and leakage. So far this bar or rafter is composed of one piece of sheet metal folded upward, as two halves, so that an under cap is formed of the same piece and no joint exposed below, and thereby all leakage between the two halves or sides entirely prevented. The above-described part of the bar is all intended to be located below the glass plates. The remaining portion of the bar or rafter consists of a bar of pliable, ductile, or flexible metal—such as lead or copper—formed into shape sectionally like a letter Y, it having a stem and two upwardly-spreading flanges or webs. The stem or lower web is placed down between the two sides, forming the vertical central portion of the part of the bar below the glass supporting ledges to a proper distance, and thereto secured by any suitable means, so that it forms an upward continuation thereof. The stem and flanges of the pliable metal are single, and not of doubled metal, and the flanges are intended to be located above the glass, when in a structure, and, being of pliable or flexible material, are adapted to be readily and with easy facility pressed downward flat upon the glass plates, covering the joints between the edges of the glass and the stem of this part of the bar or rafter, and thereby securing the same against leakage. When re-

glazing is necessary, the flanges may be readily bent upward to their first position, allowing removal of glass and placing of new. The flanges are again bent or flattened downward to secure the joints, as before. The pliable material thus used admits of its being pressed tightly upon the glass, fitting closely into any inequalities of the upper surface thereof and rendering the joint water-proof.

Pliable cap-plates formed of sheet metal doubled together are difficult of operation. They cannot be dressed or properly flattened down upon the glass plates, fitting snugly thereto, without their breaking. They are also double the expense, and, being of necessity of lead or soft copper, they are comparatively more costly. Pliable cap-plates formed of sheet metal doubled where they come in contact with the vertical portion of the skylight-bar, and at the points where they are riveted, prove defective through leakage, the doubling up of the cap forming a trough or gutter conducting the water to the leaky points. Besides, the double thickness is a waste of material. In consequence of these difficulties, pliable caps have not heretofore come into use.

In the accompanying drawings, Figure 1 is a vertical section of the lower or galvanized portion of the bar or rafter. Fig. 2 is a vertical section of the upper or pliable metal portion of the bar or rafter. Fig. 3 is a vertical section of the two parts of the bar or rafter in combination previous to glazing. Fig. 4 is a vertical section of the entire bar after glazing, the glass being shown in place and the joints covered.

A represents the lower portion of the bar or rafter. B represents the upper portion thereof. a a are the gutters, b the vertical central portion, and c c lateral flanges forming ledges to support glass plates. d is the stem of the upper portion, and e e the two upwardly-spreading flanges thereof. The rigidity of the metal forming the lower portion A, aided by its shape and construction, forms the sustaining element of the bar. The flexibility or pliability of the upper portion, B, affords ready means of securing the joints, when glazed, from leakage by being pressed down thereon, and facilitates reglazing when necessary. The

two parts of the bar are secured together by rivets or any other suitable means. *ff* represent glass plates.

What I claim as new, and desire to secure by Letters Patent of the United States, is—

A skylight bar or rafter composed of two parts, A B, in combination, the part A of one piece of sheet metal—such as galvanized iron—folded upward to form gutters *a a*, vertical central portion, *b*, and lateral flanges *c c*, the part B of pliable or flexible metal—such as

lead or copper—in bar form, shaped as a letter Y, in section with stem *d* and flanges *e e*, adapted to be bent horizontally after glazing, through its ductile nature, and the stem there-¹⁵of secured in the vertical central portion, *b*, of the portion A, substantially as shown and de-
scribed.

GEORGE HAYES.
